UNITED STATES PATENT OFFICE

WALTER KLEMPFT, OF DORTMUND-EVING, GERMANY

PROCESS OF MANUFACTURING FERRICYANIDES

No Drawing. Application filed June 29, 1929, Serial No. 374,957, and in Germany July 5, 1928.

In the United States patent-application Serial Number 283,120, dated June 6, 1928, I have described a process for the conversion of ferrocyanides into ferricyanides, that 5 process consisting in treating the ferrocyanides together with carbonic acid and air for some time under pressure and at an increased temperature in an autoclave. It has been found, however, that when effecting the oxidation under pressure in the presence of oxygen or air always a certain portion of the ferrocyanide remains and can be converted 10 into ferricyanide only with considerable difficulty. The percentage of the ferrocyanide 15 remaining towards the end of the procedure is different according to the kind of the ferrocyanic salt employed. When working, for instance, with ferrocyanide of calcium an oxidation up to from 95 to 97% can in general be attained without particular difficulty.

In order to obtain the ferricyanide from a solution the process can be carried out in general in this way that the solution is subjected to a fractionated crystallization. But 25 in this procedure the difficulty is encountered that only a small portion of the ferricyanide can be separated, this small portion being, unfortunately, impurified with adhering ferrocyanide, whereas a large portion of the ferricyanide remains mixed with the ferrocyanide in the mother-lye, which latter must then again be subjected to an oxidation under pressure.

It has, furthermore, been found that the 35 output in pure ferricyanide can be rendered quantitative in a simple manner by combining the process of oxidizing under pressure with the known electrolytic oxidation of the ferrocyanides. It is in this combination an 40 advantage that the final product which consists solely of pure ferricyanide and is obtained in dissolved state can be obtained in solid state, as solid ferricyanide, merely by concentration, preferably under vacuo, to the 45 commencement of the crystallization, the entire amount of the dissolved ferricyanide being then obtained perfectly free from ferrocyanides.

The current output decreases, as is known, 50 with increasing oxidation of the solution.

If only small amounts of the ferricyanide are to be oxidized electrolytically in the presence of a large amount of ferricyanide, the current output will in general be only small as the subsidiary reactions, especially the 55 arising of free ferricyanic hydracid and, in connection therewith, an alkalization of the cathode space, entail an increased loss of current, as well as of output. In order to conduct the electrolytic oxidation in such a 60 manner that secondary subsidiary reactions are obviated possibly much, the anode space must continually be kept neutral or, at the highest, moderately alkaline so that the formation of free hydro-ferricyanidacid is ob- 65 viated.

It has been proved advantageous to make use of the calcium salt for the transformation of ferrocyanide into ferricyanide. It has been found that under certain conditions the 70 CaO passing over into the cathode space separates on the cathode in such a solid state that it can be transferred to the anode space simply by exchanging the electrodes, the CaO being then used in the anode space for the 75 neutralization of the free acid.

While in the anode space the electrode is freed from the adhering lime, CaO collects meanwhile anew on the cathode, and can then be utilized anew in the anode space after 80 changing over of the conducting connections. It is, with this manner of operation, suitable for the purpose in view to fill the cathode space with lime water.

The combination of the oxidation under 85 pressure with the electrolytic oxidation of the ferrocyanides, as well as the employment of the calcium ferrocyanide, presents, besides, the advantage that also the calcium carbonate mud arising during the oxidation under pressure can be utilized in the anode space for the neutralization of the free acid.

Of course, instead of the soluble Ca-ferrocyanide also double-salts containing Ca, such as ammonium-calcium-ferrocyanide, potassium-calcium-ferrocyanide or sodium-calcium-ferrocyanide, and so on, can be used, if, in the case of the use of such insoluble Ca-salts, sufficient movement thereof in the 90 anode space is provided for. 100

I am now giving two examples as to how this improved process can be carried out:

First example

- 5 A 15%-solution of calcium ferrocyanide is treated with a mixture of air and carbonic acid in an autoclave under a pressure of about 50 atm. and at a temperature of about 100° C. Said mixture is composed of about 10 80% of air and about 20% of carbonic acid. In an hour, the ferrocyanide present is being oxidized to ferricyanic calcium, except a small rest amounting to about 5% of the original ferrocyanide. The solution is with- 15 drawn from the autoclave in which the pressure is maintained, and is divided onto the anode spaces of the battery of electrolyzers, the cathode spaces of which are filled with lime water.
- 20 The electrodes consist of sheet-nickel. On the sheet-nickel plates standing in the cathode space CaO is separated during the electrolytic oxidation which latter is carried out preferably with a slight density of the current. The cathode sheet-metal plate is, at 25 the next electrolytic oxidation, used in the anode space so that there is always an excess of lime. The strength of the current used in the electrolytic oxidation amounts 30 preferably to 0.005 amp. per square centimeter of the electrode surface. After the electrolyze has been finished in the anode space no trace of ferrocyanic calcium can be proved to be still present.
- 35 In order to obtain from the Ca-ferricyanide other ferricyanides, for instance the potassium-ferricyanide, the solution leaving the electrolyzer is converted with an equivalent amount of potassium carbonate. After the 40 separated calcium carbonate has been filtered off, the solution is concentrated in known manner under vacuo in order to obtain the pure potassium-ferricyanide.

Second example

- A 15%-solution of calcium-ferrocyanide is conveyed from a store receptacle into a washing space able to stand a high internal pressure. In this space said solution trickles 50 counter to a mixture of oxygen and carbonic acid which is compressed to about 50 atm. and contains about 20% of the carbonic acid. The reaction temperature is maintained on about from 120 to 150° C. After the solution has streamed one time through the reaction space or tower in which said high pressure is continually maintained it can be withdrawn; it is, except the few percents of ferrocyanide which must be oxidized electrolytically, free from ferrocyanide. The amount 55 of air or oxygen and carbonic acid consumed is again re-conducted to the current of gas.

I claim:

- 60 1. The process of converting ferrocyanide in solution to ferricyanide which comprises

treating the solution of ferrocyanide in a closed vessel under a pressure above atmospheric and at a high temperature with a gaseous mixture containing free oxygen and carbon dioxide until the greater part of the ferrocyanide is converted into ferricyanide, then withdrawing the solution from the said vessel and effecting the conversion of the remaining ferrocyanide to ferricyanide by electrolysis of the solution.

70 2. The process of converting calcium ferrocyanide in solution to calcium ferricyanide which comprises treating the solution of calcium ferrocyanide in a closed vessel in the presence of air and carbon dioxide until an equilibrium is obtained and the greater portion of the calcium ferrocyanide has been converted to calcium ferricyanide, then withdrawing the solution from the vessel and effecting the conversion of the remainder of the calcium ferrocyanide to calcium ferricyanide by electrolysis.

75 3. In the electrolysis of a solution containing calcium ferrocyanide for the conversion of said calcium ferrocyanide to calcium ferricyanide, the step which comprises employing as the anode in said electrolysis an electrode which has been employed as cathode in a previous similar electrolysis and which has thereby been coated with calcium oxide.

80 4. The process of converting calcium ferrocyanide in solution to calcium ferricyanide which comprises subjecting the solution of calcium ferrocyanide to a pressure of not less than 50 atmospheres and a temperature of not less than 100° C. in the presence of air and carbon dioxide until an equilibrium is reached and the greater part of the calcium ferrocyanide has been converted to calcium ferricyanide, then transferring the solution to the anode of an electrolytic vessel and effecting the conversion of the remaining calcium ferrocyanide to calcium ferricyanide by electrolysis, the anode employed being an electrode employed as cathode in a previous similar operation and thereby coated with calcium oxide.

85 100 In testimony whereof I affix my signature.
WALTER KLEMPFT.
